ABSTRACT: An apparatus for exposing specimens to sunlight which is always pointed directly at the sun. Electrical circuits are provided which produce an output corresponding to the path of the sun across the sky at the particular location of the apparatus for each successive day of the year so that the specimen holder is always pointed in the direction from which the rays of the sun are coming.

APPARATUS FOR EXPOSING SPECIMENS TO MAXIMUM AMOUNTS OF SUNLIGHT

This invention relates to an apparatus for exposing specimens to sunlight and weather. The specimen-carrying means is driven by driving means which is provided with circuits for reproducing the solar orbit and controlling the drive means to drive the specimen-carrying means so that the specimens are exposed to direct sunbeams all the time. The drive means is driven to follow both the sun's azimuth and altitude, so that fading and weathering tests may be carried out rapidly.

In conventional testing methods for fading and weathering, samples are tested by placing them on a frame inclined at an angle of 45° and fixed so as to face to the south.

Because of the frame base is fixed with respect to the position of the sun which is moving over the course of time, such samples are exposed to the sunlight in an inefficient manner, and much time must be spent for exposure before test results can be obtained.

For effective exposure to sunlight during exposure tests, a device which is always directed toward the sun or which can follow the sun, is needed. However there are difficult problems to solve in devising means to follow the sun for any length of time. For example, such mechanical means as are already employed with astronomical telescopes are usually only for following the rotation of the earth, and their ability to follow the sun is limited. Such means will not be very useful for perfect following of the sun because of the necessity for manual adjustment at each time of observation or at least once a day.

In a weathering test a device is required which can be operated continuously without any adjustment for at least 1 year. Therefore, such means as described above are not suitable.

Another means which has been used is an electrical means which drives the specimen carrying means to follow the sun by balancing a number of photovoltaic cells or photoelectric tubes greater than two and on which the sun's image or beams are received. However, the operation of such means depends on good weather conditions, and becomes less sensitive with deterioration of such light receptors. For these reasons this means is not satisfactory.

The disadvantages of the prior art devices are eliminated by the apparatus of the present invention, in which a device for carrying out exposure tests is provided which is able to follow the sun for a 1 year time period on the basis of calculation of the solar orbit.

The invention will be described in greater detail in connection with the accompanying drawings, in which:

FIG. 1 is a diagram showing circuits for calculation of the sun's path and control of the apparatus;

FIG. 2 is a perspective view of a practical mechanism including the circuits of FIG. 1;

FIG. 3 is a perspective view of the exterior of a unit incorporating the mechanism of FIG. 2;

FIG. 4 is a perspective view of an exposure test device;

FIG. 5 is a diagrammatic view showing movement in the azimuth direction as viewed from above the specimen-carrying frame;

FIG. 6 is a similar view showing movement in the altitude angle viewed from the side of the specimen-carrying frame;

FIG. 7 is a graph showing the relation between seasonal time and the sun's altitude; and

FIG. 8 is a graph showing the relation between seasonal time and the azimuth angle.

The altitude and azimuth of the sun at any time is given by formulas; $\sinh = \sin\phi \sin \delta \cos\phi \cos\alpha$ (1) $\sinh \sin\phi = \sin \delta = \cos h \cos\phi \cos\alpha$ (2)

where

ϕ : latitude at the point of exposure

δ : declination at the time of exposure (for example; -23° in Jan. Tokyo and +22° in June)

h : Hour angle (0° at the southing, 15° for 1 hour)

α : altitude of the sun from a level surface

α : azimuth

FIGS. 7 and 8 are graphs showing values obtained by calculation based on formulas (1) and (2) of the altitude and azimuth at Tokyo at the vernal equinox, the summer solstice, and the winter solstice.

5 Control of driving means to cause the apparatus to follow the sun is by a device formed of electric circuits as shown in FIG. 1 and a mechanism using two cams 9 and 17 as shown in FIG. 2 in combination therewith. Voltage output to satisfy the above formulas (1 and 2) is balanced to control the altitude and azimuth angle by means of servomotors.

A circuit including voltage detector G_1 is provided at the upper part of section 1 in FIG. 1 for calculating the altitude of the sun according to formula (1). A circuit including voltage detector G_2 is provided at the upper part of the section 2 for moving the device to the altitude thus calculated. A circuit including voltage detector G_3 at the lower part of section 1 for calculating the azimuth angle according to Formula (2), and a circuit including voltage detector G_4 is provided at the lower part of section 2 for moving the device to the azimuth thus calculated.

10 R_1 to R_{12} are variable resistances all having stationary elements and movable elements. Eight of the resistances, R_1 to R_4 and R_5 to R_{10} are wire wound resistances, which respectively vary as a trigonometric function, the sine or the cosine of the rotary angle of 360°, as indicated in the drawing

15 R_5 , R_6 , R_{11} , and R_{12} are resistances linear with respect to the rotary angle of 360°.

R_1 is equivalent to $\cos t$, R_2 to δ , R_3 to $\sin \delta R_4$ to $\sinh$, R_7 to $\sin h$, and R_8 to $\sin \delta$, R_9 to $\cos \alpha$, R_{10} to $\cos h$, R_5 and R_6 to the altitude h , and R_{11} and R_{12} to the azimuth angle α .

20 The movable elements of resistances R_2 , R_3 and R_8 are fixed on one shaft to be rotated together thereon as indicated by dotted lines, and the movable elements of resistances R_4 , R_5 , R_7 and R_{10} are mounted on another shaft, also as indicated by dotted lines, and the movable elements of resistances R_9 and R_{11} are mounted on a third shaft.

25 The movable elements of resistances R_2 , R_3 and R_8 are fixed on one shaft to be rotated together thereon as indicated by dotted lines, and the movable elements of resistances R_4 , R_5 , R_7 and R_{10} are mounted on another shaft, also as indicated by dotted lines, and the movable elements of resistances R_9 and R_{11} are mounted on a third shaft.

30 Separate DC voltage sources E_1 to E_{10} such as batteries or output from a voltage regulator are connected across the various resistors.

35 Sources E_1 , E_4 , E_6 , E_7 , E_9 , and E_{10} have the same potential E , and the voltage of source E_2 is multiplied by $\tan \phi$ so that, for example, if $\phi=35^{\circ}39'$, then $\tan \phi=0.71725$, and voltage $E_2 = 0.71732E$. Source E_3 is voltage E divided by $\cos \phi$ and sources E_8 and E_9 are voltage E multiplied by $\sin \phi$ and $\cos \phi$ respectively.

40 Sources E_1 to E_4 include servoamplifiers and are coupled to servomotors 20, 39, 18 and 33 respectively.

45 D is a time axle which is driven by clock or synchronous motor so as to make one station per day and is coupled to the rotary shaft of resistance R_1 .

50 A cam mechanism S is coupled to the stationary element of resistance R_1 for moving it slightly for correcting for seasonal changes at the time of culmination (the time when the sun is due south). The range of angles through which cam mechanism S is rotated is about $\pm 15^{\circ}$.

55 A cam mechanism Y is provided for converting an annual change in the declination of the sun into an angular quantity by turning the rotary shaft connected to resistances R_2 , R_3 and R_8 .

60 The section 1 enclosed by a chain line in FIG. 1 is structurally embodied as shown in FIG. 2 and is housed in the unit of FIG. 3. In FIG. 1 section 2 servomotors 39 and 33 correspond to servomotors 39 and 33 in FIG. 4. Similarly R_6 and R_{12} correspond to resistances 31 and 40 in FIG. 4.

65 Now the principal of operation will be explained. In the circuit for calculation of altitude of FIG. 1 the voltage E_1 is divided by resistances R_1 and R_2 with the output voltage of resistance R_2 being $E_1 \cos t \cos \delta$. The voltage E_2 is divided in resistance R_3 with the output voltage being $E_2 \tan \phi \sin \delta$. The voltage E_3 is divided in resistance R_4 with the output voltage being

$$70 E_3 \frac{1}{\cos \phi} \sin h$$

The output voltages from resistances R_2 and r_3 are added, the resistances being connected in series, and thus the potential on the left side of voltage detector G_1 is: $E_1 \cos t \cos \delta + E_2 \tan \phi \sin \delta$. When this potential is balanced with the potential on the right side, the equation

$$E_1 \cos t \cos \delta + E_2 \tan \phi \sin \delta = E_3 \frac{1}{\cos \phi} \sin h$$

is obtained.

By eliminating E from the above equation, as $E_1 = E_2 = E_3$, $\cos \phi (\cos t \cos \delta + \tan \phi \sin \delta) = \sin h$ or $\sinh = \sin \phi \sin \delta + \cos \phi \cos \delta \cos t$ is obtained. Thus, formula (1) is satisfied.

Likewise in the circuit for calculation of azimuth angle with voltages E_6 , E_7 and E_8 , formula (2) can be satisfied at the voltage detector G_3 .

Cost is set by continuously rotating the time shaft D of resistance R_1 at a speed of one rotation per 24 hours with resistances R_4 and R_9 being balanced by the servomotors in voltage detectors G_1 and G_3 , and the variation in the time of southing for one a year is corrected by the cam S and declination corrected by the cam Y . In this manner the values for altitude and the azimuth from the left side of equations (1) and (2) are automatically set in resistances R_4 and R_9 respectively through a year through voltage detectors G_1 and G_3 , and thence to resistances R_5 and R_{11} through the mechanical connections.

Voltages E_4 and E_5 in the control circuit for controlling elevation are divided by resistances R_5 and R_6 respectively and output voltages from resistances R_5 and R_6 are detected by G_2 and resistance R_6 is balanced to equal resistance R_5 . The servomotor 39 coupled to this voltage detector is also used as power for the exposure test device (FIG. 4) and operated so as to make the value of an angle calculated and fed to R_6 equal to that of the resistance R_5 . A similar arrangement for the azimuth is provided by resistances R_{11} and R_{12} and servomotor 33 .

Referring now to FIG. 2, one mechanical embodiment will be described. One group 4 of variable resistances corresponding to resistances R_2 , R_3 and R_8 of FIG. 1, all of which are related to the declination angle δ , are mounted on plate 3 around a shaft 4' with the movable elements on the shaft 4', while resistance 5 which corresponds to resistance R_1 of FIG. 1 is mounted on plate 3 around shaft 5' with the rotatable element mounted on shaft 5'. Shaft 5' corresponds to shaft D of FIG. 1. A further group 6 of resistances corresponding to resistances R_9 and R_{11} of FIG. 1, all of which are related to the azimuth angle, are mounted on plate 3 around shaft 6' with the movable elements on the shaft 6', while a still further group of 7 of resistances corresponding to resistances R_4 , R_5 , R_{10} and R_7 , all of which are related to the altitude angle h , are mounted on plate 3 around a shaft 7' with the movable elements on the shaft 7'. The shaft 5' is driven by a synchronous motor 10 through gearing 10' so as to rotate once each 24 hours, and the gearing 10' is connected to shaft 22 mounted on plate 3 through reduction gearing 11 so as to rotate the shaft 22 once each year. Mounted on shaft 22 are cam 17, corresponding to the cam S of FIG. 1, and cam 9, corresponding to cam Y of FIG. 1. Cam follower and lever systems 16 is coupled between cam 17 and the resistance 5 to rotate the body of resistance 5 slightly in response to the rotation of the cam 17 for correcting for seasonal changes of the time of southing, and cam follower and lever system 8 is coupled between cam 9 and the shaft 4' to rotate shaft 4' to correct for the annual change in the declination of the sun. Dials 12 and 13 can be provided on shafts 22 and 5** to indicate the hour and the day. Dials 19 and 21 can be provided on the shafts 6' and 7' to indicate the azimuth and elevation. Servomotors 18 and 20, mounted on plate 3, are geared to shafts 6' and 7' respectively for rotating the shafts in response to voltages from the voltage detectors G_3 and G_1 .

FIG. 3 shows the external appearance of a unit in which the mechanism as described above is housed. Servoamplifiers 24 and a voltmeter 23 for checking DC voltage are also provided in the housing.

On the rotary portion of the reduction gears 11 and of the motor 10 there can be provided some sliding means or a clutch for adjustment of data and time by manual control of the dials 12 and 13. If night operation is not required, a time switch or the like may be mounted on the rotary portion of the shaft 5'.

The specimen-carrying part of the apparatus is shown in FIG. 4 and has a box 30 mounted on a base 29, in which a shaft 32 which is rotatable around a vertical axis (for the azimuth), the servomotor 33, and a resistance 31 corresponding to resistance R_{12} in FIG. 1 are provided and engaged through gears.

The shaft 32 has fixed on the upper end a box 34, which is rotated horizontally by means of the servomotor 33 by rotation of shaft 32.

On the slanting upper surface of the box 34 is mounted a shaft 35 with frames 37 mounted on the back of a metal or wooden specimen-carrying board 36 mounted on shaft 35 so as to be rotated through the angle corresponding to the altitude of the sun. A balance weight 38 is mounted on one frame 37. A servomotor 39 for the controlling altitude and a resistance 40 for the altitude and corresponding to resistance R_4 in FIG. 1 are mounted in box 34. The shaft 35 is rotated by gears having a suitable reduction ratio. A clutch lever 41 is provided for cutting off or transmitting driving power between the shaft 35 and the motor 40. This is provided in order to permit manual setting of the specimen-carrying board at any desired position so that samples may be easily attached to or detached from the board. The positions of specimens are shown at 42.

FIG. 6 is a side view of the specimen-carrying board, showing the position thereof, where sunbeams are incident thereon as indicated by arrows, and the angle h of inclination shows the altitude of the sun.

FIG. 5 is schematic diagram of the specimen-carrying board viewed from above, where α is the azimuth angle, covering 120° at a maximum from the south to the north and to the west respectively.

The present apparatus is very easy to handle and operate. First the specimen-carrying board 36 is moved by hand to position for easy attachment or detachment of samples after actuation of the clutch lever 41 to disconnect the board, and then the clutch is reengaged. The day dial 12 and the time dial 13 are set to the corresponding day and time, and a power switch (not shown) is turned on. The circuit for calculation and control starts to operate so as to cause the device to follow the sun all the times for carrying out exposure tests.

Exposure tests on various kinds of dyed goods using the device of this invention show that they are faded two or three times quicker than those tested on conventional exposure apparatus which is fixed facing to the south.

I claim:

1. An apparatus for exposing specimens to sunlight, comprising a specimen-holding member; mounting means on which said specimen-holding member is mounted, said mounting means being movable in azimuth and elevation; two driving servomotor means coupled to said mounting means, one for driving the mounting means in azimuth and the other for driving the mounting means in elevation; two driving voltage divider means, an azimuth voltage divider means and an elevation voltage divider means, each having a voltage detector therein coupled to the respective driving servomotor, the driving servomotor also being coupled to the respective voltage divider means to balance them in response to a detected voltage difference; an elevation determining circuit having a voltage divider means therein and voltage-resistance means coupled therein for balancing said elevation determining circuit voltage divider means according to the formula

$$\sinh = \sin \phi \sin \delta + \cos \phi \cos \delta \cos t$$

in which

ϕ is the latitude at the point of exposure

δ is the declination at the time of exposure

t is the hour angle

α is the azimuth

said elevation determining circuit voltage divider means being coupled to said elevation voltage divider means for unbalancing the elevation voltage divider means in response to the balancing of said elevation determining circuit voltage divider means, and means for varying the voltage-resistance means over a 24-hour time period in accordance with the elevation of the sun; and an azimuth determining circuit having a voltage divider means therein and voltage-resistance means coupled therein for balancing said azimuth determining circuit voltage divider means according to the formula $\sin h \sin \phi - \sin \delta = \cosh \cos \phi \cos \alpha$ in which h is the altitude of the sun from a level surface and the remaining terms are the same as in the equation for elevation, said azimuth determining circuit voltage divider means being coupled to said azimuth voltage divider means for unbalancing the azimuth driving voltage di-

vider means in response to the balancing of said azimuth determining circuit voltage divider means, and means for varying the voltage-resistance means over a yearly period according to the change in declination of the sun.

5 2. An apparatus as claimed in claim 1 further comprising an elevation correction means is coupled to said elevation determining circuit for feeding a correction to said voltage-resistance means to correct for annual changes in elevation.

3. An apparatus as claimed in claim 1 further comprising a 10 drive motor for said mounting means and clutch means coupled between said drive motor and said mounting means for enabling drive of said mounting means when said clutch is engaged to set the specimen-holding member in the proper position to start operation of the apparatus.
